UNITED STATES PATENT OFFICE.

WILLIAM J. HOGG, OF PHILADELPHIA, PENNSYLVANIA, ASSIGNOR TO
WILLIAM HOGG, JR., OF SAME PLACE.

DESIGN FOR CARPETS.

Specification forming part of Design No. 6,357, dated January 21, 1873.

To all whom it may concern:

Be it known that I, WILLIAM JAMES HOGG, of Philadelphia, Pennsylvania, have produced or invented a Design for a Carpet-Pattern, of which the following is a specification:

The figure in the accompanying drawing represents sufficient of the border A and body B of a carpet to illustrate my design.

The border A consists of a series of parallel ribs, *a b c d*, &c., of different shades or colors, some of which are discontinued or broken at intervals, and composed wholly or in part of short transverse and inclined bars forming figures of the same general character as those composing the body of the pattern. The body B is made up of a series of figures, *f*, arranged at regular distances apart, and each consisting of a central dot surrounded by an angular bor-

der, and the figures are separated into longitudinal rows by zigzag ribs *g* of the character represented in the drawing.

Irrespective of the colors employed, I claim—

1. The design for the border A, substantially as shown and described.
2. The design for the body B, substantially as described and represented.
3. The design for a carpet-pattern in which the border A and body B are combined.

In witness whereof I have signed my name to this specification in the presence of two subscribing witnesses.

W. J. HOGG.
